UNITED STATES PATENT OFFICE.

JULIA A. CALLAHAN, OF BROOKLYN, NEW YORK.

OPERA-CHAIR.

SPECIFICATION forming part of Letters Patent No. 351,899, dated November 2, 1886.

Application filed October 21, 1885. Serial No. 180,519. (No model.)

To all whom it may concern:

Be it known that I, JULIA A. CALLAHAN, of Brooklyn, in the county of Kings and State of New York, have invented certain new and useful Improvements in Restaurant and Theater Chairs, of which the following is a full, clear, and exact description.

The invention consists in the construction and combination of parts and details, as will 10 be fully described and set forth hereinafter, and then pointed out in the claim.

Reference is to be had to the accompanying drawings, forming a part of this specification, in which similar letters of reference indicate 15 corresponding parts in both the figures.

Figure 1 is a perspective view of my improved restaurant and theater chair. Fig. 2 is a detail side view of a clothes-holding hook of a modified construction.

20 The chair A is in general of the usual construction, and to the legs a frame, B, is secured below the seat, which frame B has a railing, E, at the sides and rear. The said frame serves as a support for the hat D of the person occupying the chair, or for bundles, books, &c.

To one of the rear legs a drip-cup, F, is fastened for the purpose of receiving the lower end 30 of an umbrella-stick or a cane and catching the drip-water from the umbrella. A loop or bow, G, is either fixed or pivoted to the chair-back, and serves to hold the upper part of the stick of the umbrella H.

A curved lever, K, is pivoted to one of the 35 uprights L or side pieces of the chair-back at or near the middle of said lever. When the inner end of the lever K is swung down, the outer end is raised and does not project from the sides of the chair-back, and thus is out of 40 the way. When a garment is held on the chair-back, the said lever K is swung down, so

that its outer end projects from the side of the chair-back, the inner end resting against the inner edge of the side of the chair-back, as shown in dotted lines in Fig. 1, and thus preventing the outer end from swinging down too far. The garment is then passed over the outer end of the lever K and supported by the same.

An angle-lever, M, is pivoted on one front 50 leg, N. When not in use, the outer shank is swung up against the said leg and the inner shank is swung down, as shown in full lines in Fig. 1, and the lever is thus out of the way. When a garment is hung on the chair, the outer 55 arm or shank of the lever M is swung down, and the lower part of the garment placed on it to prevent the said lower part of the garment from coming in contact with the floor and being soiled.

In place of the curved lever K and the angle-lever M, I may provide shafts P, provided with hook-shaped arms Q, and acted upon by spiral springs R, which throw the said arm Q against the side of the chair or against the 60 back as soon as the garment is removed. The levers K and M operate in a similar manner, as their inner ends are weighted to swing down as soon as the garment is removed.

Having thus described my invention, I claim 70 as new and desire to secure by Letters Patent—

The combination, in a chair, of a garment knob or button, J, on the top of the chair-back, the hook or support K, pivoted to the side of the chair-back, and the hook or support M, 75 pivoted to the chair near its lower end, substantially as set forth.

JULIA A. CALLAHAN.
